DESIGN FOR A GARDEN CULTIVATOR

Mario J. Amendola, Los Angeles, Calif.

Application May 22, 1945, Serial No. 119,674

Term of patent 14 years

(Cl. D35—2)

To all whom it may concern:

I, Mario J. Amendola, a citizen of the United States, residing at Los Angeles, in the county of Los Angeles, State of California, have invented a new, original, and ornamental Design for a Garden Cultivator, of which the following is a specification, reference being had to the accompanying drawing, forming part thereof.

Fig. 1 is a side elevational view of a garden cultivator showing my new design.

Fig. 2 is a top view of the garden cultivator.

Fig. 3 is a front end view.

I claim:

The ornamental design for a garden cultivator, substantially as shown.

MARIO J. AMENDOLA.
